UNITED STATES PATENT OFFICE.

PETER RIESECK, OF ALLEGHENY, PENNSYLVANIA.

DESIGN FOR A WALL-TIE.

SPECIFICATION forming part of Design No. 33,342, dated October 9, 1900.

Application filed June 11, 1900. Serial No. 19,870. Term of patent 14 years.

To all whom it may concern:

Be it known that I, PETER RIESECK, a resident of Allegheny, in the county of Allegheny and State of Pennsylvania, have invented a new and original Design in Wall-Ties; and I do hereby declare the following to be a full, clear, and exact description thereof.

My design relates to wall-ties; and its characteristic feature consists of a tie having a wavy body portion and end portions extending in opposite directions and beyond the body portion, the body portion and end portions all lying in the same plane.

Figure 1 is a perspective view of my design. Fig. 2 is a top view thereof, and Fig. 3 is an edge view.

In the drawings, 1 indicates the body portion of the wall-tie, which is formed wavy, as at 2, and having one end portion 3 extend-

ing in one direction and beyond the body portion and the other end portion 4 extending in the opposite direction and beyond the body portion. As shown in the edge view, Fig. 3, the body portion and end portions of the tie all lie in the same horizontal plane, so that the wavy body portion of the tie will lie upon the brick to be tied together and the end portions extend in opposite directions upon the adjoining bricks.

What I claim is—

The design for a wall-tie as herein shown and described.

In testimony whereof I, the said PETER RIESECK, have hereunto set my hand.

PETER RIESECK.
